UNITED STATES PATENT OFFICE.

GEORGE J. AXT, OF NUTLEY, NEW JERSEY.

ATTACHMENT FOR HEMMERS.

Application filed February 28, 1922. Serial No. 539,952.

To all whom it may concern:

Be it known that I, GEORGE J. Axt, a citizen of the United States, and a resident of Nutley, in the county of Essex and State 5 of New Jersey, have invented a new and Improved Attachment for Hemmers, of which the following is a full, clear, and exact description.

This invention relates to an attachment 10 for hemmers whereby the material which is being hemmed can be very readily fed to the hem securing mechanism.

An object of the invention is to provide a very simple and readily applicable attachment for hemmers whereby the operator can very quickly and easily advance the material being hemmed to the hem securing mechanism and without any danger of injury to the fingers.

Another object resides in the provision of a very simple means which can be readily applied to and detached from any type of hemming mechanism with no necessity for altering the machine to which it is attached.

A further object resides in the particular construction and arrangement of parts which are hereinafter described and claimed and shown in the accompanying drawings.

The invention is illustrated in the drawings, of which—

Figure 1 is a plan view of the attachment applied to a hemmer.

Fig. 2 is a side elevation.

Fig. 3 is an end view from the plane 3—3 indicated in Fig. 2.

The form of the invention shown in the drawings is a preferred form, although it is understood that modifications in the construction and arrangement of the parts and in the character of the materials used may be adopted without departing from the spirit of the invention.

Hitherto in operating hemming mechanisms difficulty has been encountered in feeding the material through the scroll or device which folds the material and presents it to the hem securing apparatus. The reason for this difficulty has been, especially in the case of scrolls adapted to form fine hems, that the material would become stuck in the scroll. Operators heretofore have used their fingers or a sharp instrument such as a hat pin or scissors, and the engagement of these articles with the material, especially if it is fine material, would cause an impairment of the fabric.

In my invention I provide a finger or plate 1 having on its lower edge a plurality of teeth 2 of any desired size and number which are attached to a flat bar or plate 3. This plate or bar 3 is connected at its rear end to a sliding block 4 slideable in a groove or channel between flanges 5 and 6 formed in any desired manner on the plate 7. This plate 7 is attached by any suitable means, such as screws 8 and 9, to the scroll-supporting bar 10. The plate 3 is provided with a finger-engaging head or portion 11 and a knob 12. This head 11 and knob 12 may be connected in any desired manner to the block 4. A spring 13 connected at one end to the block 4 and at the other end to a pin 14 mounted on a rearwardly extended portion 15 of the plate 7 tends to hold the finger 1 in a withdrawn, retracted position.

This plate 7 and its co-operating parts, including the finger 1, is adapted to be readily attached to the scroll-supporting bar 10 from which the usual scroll 16 is supported. This scroll is provided on its upper face with a slot 17 and the material, as it is fed in the usual manner through the scroll, can be engaged through this slot. The finger or plate 1 is disposed normally over the slot 17, and when the finger of the operator moves the head 11 forward, the plate 3 and the finger 1, being preferably of spring metal, are advanced and slightly depressed so as to cause the teeth to come into engagement with the fabric. The engagement of the teeth 2 with the fabric will enable the fabric to be very easily and quickly advanced through the scroll to a point where the fabric is engaged by the hem-securing mechanism which is located just beyond the end of the scroll 16. When the screws 8 and 9 are removed the plate 7, the block 4, the plate 3 and the finger 1 with their co-operating parts can be removed from the scroll support.

In this manner, therefore, I have provided a simple little device which can be attached to any type of scroll for use in connection with a hemmer and by means of which the material can be very readily fed forward without injury to the material and to the hands of the operator.

What I claim is:

1. An attachment for hemmers having a scroll and a support therefor, which comprises a plate attached to the support, said plate having a channel thereon, a sliding

block mounted in the channel, a spring plate connected to the block, and a dependent finger on said spring plate, said finger adapted when operated to engage the material in the scroll to feed it.

2. An attachment for hemmers having a scroll with a slot therein and a support for the scroll, which comprises a plate attached to the support having a channel therein, a block slideable in said channel, a spring plate connected to the block, a dependent finger connected to said spring plate, and teeth on the lower edge of the finger, said finger extending into the slot and said teeth engaging the material in the scroll when operated to feed the material.

3. An attachment for hemmers having a scroll with a slot therein and a support for the scroll, which comprises a plate attached to the support having a channel therein, a block slideable in said channel, a spring plate connected to the block, a dependent finger connected to said spring plate, teeth on the lower edge of said finger, said finger extending into the slot and said teeth en-

gaging the material in the scroll when operated to feed the material, and a spring connected at one end to the block normally tending to hold the block and the finger in a retracted position, the other end of the spring being connected to the plate.

4. An attachment for hemmers having a scroll with a slot therein and a support for the scroll, which comprises a plate attached to the support having a channel therein, a block slideable in said channel, a spring plate connected to the block, a dependent finger connected to said spring plate, teeth on the lower edge of the finger, said finger extending into the slot and said teeth engaging the material in the scroll when operated to feed the material, a spring connected at one end to the block and normally tending to hold it and the finger in a retracted position, and a finger-engaging head portion connected to the block and spring plate whereby they may be advanced by the finger of the operator, the other end of the spring being connected to the plate.

GEORGE J. AXT.
